UNITED STATES PATENT OFFICE.

HERBERT M. FRIENDLY AND ARCHIBALD E. BURNS, OF PORTLAND, OREGON; SAID BURNS ASSIGNOR TO SAID FRIENDLY.

TOLL-TELEPHONE SWITCHING APPARATUS.

1,394,723.

Specification of Letters Patent.

Patented Oct. 25, 1921.

Application filed June 7, 1915, Serial No. 32,767. Renewed March 1, 1921. Serial No. 448,869.

To all whom it may concern:

Be it known that we, HERBERT M. FRIENDLY and ARCHIBALD E. BURNS, residents of Portland, Multnomah county, Oregon, have invented certain new and useful Improvements in Toll-Telephone Switching Apparatus, of which the following is a specification.

Our invention in its fullest embodiment consists in means for remotely effecting connection and disconnection of toll lines, and of providing visual and auditory signals, and other means to facilitate the operation of same alone and in conjunction with independent lines adapted to be connected with said toll lines. An object is to reduce the manual effort necessary in methods heretofore employed in establishing such service.

Conditions met in practical telephone operation vary in electrical structural and operative details due to manifold reasons. The peculiarities of electrical circuits and devices incident to individual switchboards, as well as the varied conditions of traffic and the handling of same, demand subordinate and detailed modifications of our invention for practical and commercial application to specific cases. So it is impossible to devise apparatus for such varied adaptations and means of employing it, the object of which is to perform certain functions and then apply universally to all toll lines and incident equipments the devices with details unchanged. Therefore, the specifications and accompanying drawings hereof illustrate and refer only to one of many possible and practicable applications of our invention. It is manifest that features of our invention can thus be employed as an amplification, or without its adoption as an entirety, and that the details of construction and operation can be varied and applied within wide limits and without departing from its scope by those skilled in the art to which it belongs.

In the accompanying drawings:

45 Figure 1 is a diagrammatic conventional representation of two toll lines adapted to be interconnected and disconnected.

Fig. 2 is a diagrammatic conventional representation of essential parts of a common form of connecting-cord circuit adapted to use in connection with Figs. 3, 4 and 5, and independent lines.

50 Fig. 3 is a diagrammatic conventional representation of the essential parts of equipments and electrical circuits as used at the

point of interconnection as at the station A3, Fig. 1.

Fig. 4 is a diagrammatic conventional representation of the essential parts of equipments and electrical circuits as used at the 60 station A4, Fig. 1.

Fig. 5 is a diagrammatic conventional representation of the essential parts of equipments and electrical circuits as used at the station A5, Fig. 1.

65 Fig. 6 is a front elevation of the frame containing a portion of the apparatus shown as associated with the switchboard equipment proper, Fig. 4.

Fig. 7 is a side elevation of a dustproof 70 and cross-talk proof cover adapted to go over front of Fig. 6 to inclose relays.

Fig. 8 is a right side elevation of frame shown in Fig. 6.

Fig. 9 is a plan elevation of terminal rack 75 and rocking switch shown at top of Fig. 6.

Fig. 10 shows a detail of member 43, used for carrying relay R5. Members 41 and 42 are similar.

Fig. 11 shows details looking to right of 80 section A—B, Fig. 10.

Referring to the figures in detail:

Fig. 1 shows an application of our invention as applied to two toll lines adapted to be used as one continuous line. The dotted lines at A3 denote a possible connection between the two lines D and E; s1, s2 and s3 denote bridging signals of common types connected at stations on line E; and s4, s5 and s6 denote similar signals at stations on 90 line D. 1 and 2 refer to terminals of equipment set corresponding to the same designations in Fig. 4; 3 and 4, 5 and 6 correspond to terminals of an equipment set corresponding to the same designations in Fig. 3; 7 and 95 8 refer to terminals of an equipment set corresponding to the same designations in Fig. 5. Thus, A4 denotes Fig. 4; A3 denotes Fig. 3; A5 denotes Fig. 5.

A function of the arrangement indicated 100 by Fig. 1, which we will use to exemplify and elucidate our invention, is:

To enable an operator at station A4, for instance, to signal and establish a telephonic connection along the line D; also to similarly 105 enable an operator at station A5, for instance, to signal and converse along the line E; further to incidentally enable the operators at stations A4 and A5 to cause the lines D and E to be interconnected and dis- 110

connected at will, at the station A3; further, to permit operators at stations shown to interconnect local or independent lines with the lines specifically indicated by means of 5 a common form of cord sets. There are other incidental functions which will be referred to later in these specifications and subjoined claims.

In the following, we will describe the 10 physical operations and incident electrical functions attending the establishment and disestablishment of a telephonic connection between station A4 on line E and station s6 on line D, under control of the operator at 15 station A4, Fig. 1.

Referring to Fig. 4, the terminals of springjacks J1, J2 and J3 are in multiple relation; also, the terminals of springjacks J4, J5 and J6 are in multiple relation; also, 20 the terminals of the lamps j1, j2, j3, j4, j5, j6 associated with and drawn immediately above the said springjacks respectively are in multiple relation, one side of which circuit is connected to battery B1.

25 For convenience of description, we will term the jack J3 the regular answering jack, and associated jacks J1 and J2 regular multiple jacks. In a like manner J6 will be termed the regular through switching jack, 30 and associated jacks J4 and J5 will be termed through switching multiple jacks. The functions and uses of jacks J1, J2 and J3, and J4, J5 and J6 are the same respectively. So, for further convenience of description, 35 we will refer to jacks J3 and J6 respectively, omitting mention of their said multiplied jacks.

In Fig. 4, it will be observed that terminals e1, e2; e4, e5; e7, e8, respectively, of 40 jacks J1, J2 and J3, are directly connected with terminals 1 and 2 normally, and thus stations as s1, s2, s3 and A3, Fig. 1, are normally conductively associated with J1, J2 and J3 by way of conductors i4 and i5, 45 while the terminals e10, e11, e13, e14, e16, e17, respectively, of jacks J4, J5 and J6, are only connected to terminals 1 and 2, over conductors i2 and i1 respectively, after a plug as p1 has been inserted into one of 50 the latter jacks. Further, as will be shown later, the interconnection of lines E and D at station A3, Fig. 1, is accomplished simultaneously with the insertion of said plug p1 into jack J6, Fig. 4, thus obtaining access 55 to the line D from station A4 on line E. Referring again to Fig. 4, relays R1 and R2 are in multiple relation with relay 2R, the circuit including the relay R2 being through the contacts 1c-2c, 3c-4c and 5c-6c of 60 pushkeys n1, n2 and n3 respectively. Thus upon inserting plug, as p1, into any one of the jacks J4, J5 or J6, relays 2R, R1 and R2 will actuate directly. The function of relay 2R has been described. Bearing in mind the 65 actuated conditions of both relays R2 and

2R, the function of relay R1 is: First, to ground conductor i3 through contacts a2-a3. This will energize relay 1R, thus disassociating signal device D1 over regular answering jack J3, at contacts 3r-4r and 5r-6r and also close circuit through lamp j3 and its multiplied lamps j1, j2, j4, j5 and j6 by way of 1r-2r to ground G1, the latter closed contacts being in multiple with similarly related contacts, 7r-8r, of relay 2R. Second, 70 relay R1 opens contacts a4-a5, making contacts a5-a6, thus changing the ground applied to terminal b6 of polarized relay R5 to battery F, and removing the ground normally on terminal b1 by the contacts a1-a2 75 opening. The latter contacts opening render the relay R5 ineffectual by virtue of destroying its secondary or local circuit continuity from its said terminal b1. 80

Relay R5 is differentially connected 85 between its terminals b7 and b8. That is, any currents applied serially between these terminals will not exert a tractive effort on the armature b5. However, to currents applied through the said relay in derivation from terminal b6, armature b5 of said relay will be directionally operative. Currents from battery F tend to operate its armature b5 in its indicated plus direction and further open contacts b1-b2 and b3-b4 respectively. 90

For convenience, we will refer to certain polarized relays as operating in a plus or minus direction, arrows indicating movement of the end of armature. 100

Repeating coil or inductorium C1 is made up of two inductively related windings, which for convenience will be termed primary and secondary windings. The primary winding is made up of two sections d1-d2 105 and d5-d6 connected cumulatively in series. The secondary winding is made up of sections d3-d4 and d7-d8, the latter section windings corresponding with the primary windings as regards direction. 110

Battery current from battery F finds its way derivatively to terminals 1 and 2 from contacts a12-a11; thence to contacts a6-a5; thence to relay terminals b6-b9; thence cumulatively through relay R5 to terminals b7 and b8; thence to terminals d4 and d8 of secondary windings of repeating coil C1; thence from terminals d3 and d7 respectively to line terminals 1 and 2, Fig. 4. 115 From the latter terminals the derived currents are conducted in parallel over the limbs of the line E, Fig. 1, to terminals 3 and 4, Fig. 3, which is shown as station A3, Fig. 1; thence through contacts g44-g45 and g46-g47 respectively of relay 3R; 120 thence to terminals g5 and g7 of polarized relay R6; thence differentially to terminal g10 of same relay. From said terminal g10 there are two paths to terminal g11 of relay R8 in derived relation. One path is 125

serially by way of contacts $g1-g2$ and $g3-g4$, relay R6; thence to terminal $g16$, relay R7; thence serially through relay R7 to terminal $g18$; thence through contacts 5 $g26-g27$ and $g28-g29$, relay R8; thence through relay R10 by way of terminals $g73$ and $g74$; thence to common or junction point $g11$. The other path from $g10$ to $g11$ is through the associated relays R7', R7'' and 10 resistance $g21$, the detailed operation of of which will be explained later. From terminal $g11$ the current path is differentially through relay R8 to terminals $g22$ and $g24$ thereof; thence through contacts 15 $g57-g58$ and $g59-g60$ respectively of relay 5R; thence to terminals 5 and 6; thence in parallel over line D, Fig. 1, to terminals 7 and 8, Fig. 5. Fig. 5 is shown as station A5, Fig. 1. The description in detail of Fig. 20 5 will be taken up later. Suffice it to state here that with apparatus in Figs 3 and 4 in the position described, current from grounded battery F, Fig. 4, flows to terminals 7 and 8 over parallel paths to ground 25 at G3, Fig. 5, as follows:

From terminals 7 and 8, Fig. 5, the circuit may be traced to terminals $e7'$ and $e3'$; thence through the sections of the secondary windings of said repeating coil C2; thence 30 to terminals $f39$ and $f48$ respectively of relay R17 by way of terminals $e8'$ and $e4'$ respectively; thence cumulatively through windings R17 to terminal $f38$; thence through contacts $f7-f6$ of relay R12 to 35 ground G3. Indicated windings of repeating coil C2 are similarly disposed to the indicated windings of coil C1, Fig. 4.

Relay R6, Fig. 3, is a polarized relay bridged between terminals 3 and 4 by way 40 of contacts $g44-g45$ and $g46-g47$ respectively of relay 3R. Relay R8 is a similar relay bridged between terminals 5 and 6 by way of contacts $g57-g58$ and $g59-g60$ respectively of relay 5R. The section windings of relays R6 and R8 are so disposed 45 with regard to terminals $g10$ and $g11$ respectively that any currents passing to or from said terminals are equally and differentially divided through the windings of the 50 respective relays and will thus produce no effect as regards any tractive effort on armatures $g9$ and $g30$ respectively.

All currents passing through the polarized relay R7 by way of terminals $g16$ and 55 $g18$ will exert a tractive effort upon the armature $g20$, which controls contacts $g12-g13$ and $g14-g15$, normally open. Relay R7 being sensitive to directional currents and the current from battery F, Fig. 60 4, being negative, since the battery F has its positive pole grounded, the current from battery F is therefore assumed to pass into relay R7 at terminal $g16$ and out of it at terminal $g18$. The relay R7 is designed to 65 move its armature $g20$ so contacts $g12$ and

$g14$ are placed into electrical conductivity with contacts $g13$ and $g15$ respectively, upon the passage of said negative currents from battery F. We therefore refer to said movement of armature $g20$ as having moved in a 70 minus direction as designated by arrows. Incidentally, currents emanating from a battery or other source substituted for battery F, having the negative pole grounded, will project currents of opposite direction 75 through relay R7 and cause its armature $g20$ to move in a direction opposite to that required to close its contacts $g12$ and $g14$ with $g13$ and $g15$ respectively or in a plus direction. Relay R7 is thus designed to 80 close contacts $g12-g13$ and $g14-g15$ upon passage of negative currents or currents in direction from $g16$ to $g18$ only. The object of this directional characteristic in relay R7 will be shown later.

Relay R9 is controlled supplementarily by said contacts $g12-g13$ and $g14-g15$, and therefore by the direction of parallel or derived currents applied to terminals 3 and 4 over line E. Relay R9 in turn will, through 85 contacts $g33-g34$ and $g35-g36$, complete the telephonic circuit between terminals 3 and 4, and 5 and 6. The condensers $t1-t1$ and $t2-2t$, while transparent to ordinary telephonic and alternating currents, are 90 opaque to the direct and constant currents for manipulation, such as are applied to normally actuate relay R7 as described. Thus all manipulative currents to, from, or 95 between the lines E and D are constrained 100 to normal paths regardless of the position of relay R9.

Relays R11 and R9 are in secondary or local relation to relay R10, and furthermore the relay R9 is dependent upon the primary 105 operation of relay R10. Upon relay R10 acting in response to currents coming from battery F, as previously described, relay R11 will be actuated by current from local battery B2 to ground through contacts 110 $g37-g38-g39$ of relay R10. The action of relay R11 causes multiplied lamps $j21$ and $j22$ to glow through contacts $g41-g40$; also the action of relay R10 causes ground G2 to be applied to contact $g12$, relay R7, 115 through contacts $g38-g37$. Thus it will be observed the following cycle of operations must ensue before relay R9 can obtain actuating current and close the telephonic connection between terminals 3 and 4, and 5 120 and 6 by its contacts $g36-g35$ and $g34-g33$ respectively; the actuation of relay R7 in the indicated minus direction, thence successively relays R10 and R9. The object of this succession of relay functions is to retard, by reason of inertia and inherent relay 125 time element, any current impulse applied to the said limb of the derived circuits between $g10$ and $g11$, to a degree sufficient to prevent relay R9 from obtaining actuating 130

current before the cessation of the said current impulse. However, to sustained currents the cycle of operations will become completed and the closing of the telephonic connection between 3-4 and 5-6 will be accomplished as long as current is sustained from battery F to ground G3. To further forestall occurrence of false interconnection or telephonic interference between the lines 10 D and E, Fig. 1, by reason of signal impulses or alternations, for instance, applied between the limbs of the telephonic circuit, the derived limb between g10 and g11 including the relay R10 is carried through 15 contacts g1-g2 and g3-g4, relay R6, and contacts g26-g27 and g28-g29 of relay R8. The polarized relays R6 and R8, being bridged between terminals 3 and 4, and 5 and 6 respectively, as previously described, 20 currents of proper character applied between the limbs of the telephonic lines will actuate its corresponding relay R6 and R8, as the case may be, or possibly both of said relays, if relay R9 is actuated. Thus, when a 25 bridging current is applied between terminals 3 and 4 or 5 and 6, as a single phase ringing current, for instance, the derived limb including relay R10 will be opened, thereby making an interconnection of the 30 lines D and E, Fig. 1, impossible.

Lamps j21 and j22, Fig. 3, are located so as to indicate to separate operators at station A3 when lines D and E, Fig. 1, are interconnected. The said lamps are under the 35 control of relay R11, and this relay having the characteristic of slow or retarded release, insures the steady glowing of said lamps during lapses in the current of short duration, to which its controlling relay R10 is 40 responsive. The occurrence of this lapse will be explained later, in connection with description of signaling functions.

A purpose of resistance involved in the 45 circuits between terminals g104 and g105, Fig. 3, is to prevent a complete opening of the manipulative circuit from battery F to ground B3 in the event of the derived limb, including the relay R10, becoming opened under conditions previously adverted to. 50 The object of retaining this circuit continuity between g10 and g11, Fig. 3, under all operative conditions, will be shown later in connection with the description of signaling functions.

55 A second purpose of the circuits and equipments R7', R7'' and g21 between the terminals g104 and g105 is to cause the cut-off relays 4R and 6R to disassociate the signal devices D3 and D4 respectively when 60 direct current is sustained through R7', as for instance, while manipulative currents are applied between the terminals 3 and 4, and 5 and 6 in parallel. Thus when lines D and E are interconnected or when a signaling current is applied through the agency

of relay R5 or relay R17, the signal devices D3 and D4 are disassociated. Other functions may also be accomplished, as actuating a relay adapted to cut off jacks during interconnection to preclude access to lines by 70 operators during duration of through connection. Current of a transitory or alternating nature as a single phase alternating current of frequencies met in telephone practice, will not cause the relay R7' to actuate by reason of its armature being retained through the tractive effort of the pole pieces of relay R7'' during the passage of varying currents as mentioned.

75 Relay R7'' is made up of two like windings connected differentially from common terminals g104 and g114; the free terminals of the respective windings connect to the noninductive resistance g21 and relay R7', joining at common point g105. The armature g110 of relay R7' has attached to it a nonmagnetic connecting yoke g106 carrying a magnetic armature piece g107 in attractive relation to opposite pole pieces g109 and g115 of relay R7''. When a current of 80 an alternating nature, for instance, passes in at terminal g10 and out at terminal g11, the upper and lower windings of relay R7'' obtain currents of unequal strength by virtue of the properties of the branches of 85 equal ohmic resistance including the relay R7' and resistance g21. Though said relay and said resistance have equal ohmic resistance, they present different impedances to currents of inconstant nature. Therefore 90 the armature piece g107 will be attracted to its related pole pieces g109 and g115 by the electromagnetic effect of the preponderant helix, preventing the armature g110, to which it is rigidly attached, from actuating 95 contacts g101-g102-g103 to apply ground G2 on contact g101 to the free sides of relays 4R and 6R, actuating them to disassociate signal devices D3 and D4 respectively. To 100 sustained direct currents of either polarity 105 the current dividing between the two windings of relay R7'' will be equal, and by reason of being differentially connected will produce a null effect upon the armature piece g107. Thus the armature of relay R7' will be unrestrained and free to close its contacts 110 g101-g102-g103, causing the relays 4R and 6R to act as before described. The described characteristics are incorporated in the equipment set R7' and R7'' and g21 so, if a 115 ground seeking alternating current, for instance, is applied from some station to signal the station A3, the signal devices will not be falsely disassociated by the actuating of relay R7'.

120 Incidental to the current passage from terminals 7 and 8, Fig. 5, to ground G3, as previously traced, the armature f50 of relay R17, is in the indicated plus direction, thus closing its contacts f44-f45 and f46-f47 130

respectively. As a consequence of the closing of the said contacts, current flow is established between battery B3, which is common to one of the common wires, forming the 5 multiple connection between the lamps j_7 , j_9 , j_{12} , j_{14} , j_{16} and j_{19} ; over the other common wire $6i$ of said lamps; through said contacts of relay R17; through relay R16 by way of its terminals f^{35} — f^{34} ; to ground G3 by way 10 of contacts f_3 — f_4 of relay R12. By virtue of this current through relay R16, its contacts f^{36} — f^{37} will open. This opening of contacts will open the conductor $7i$ between the multiplied terminals e_{30} , e_{33} and e_{36} 15 respectively of jacks J10, J11 and J12, the object of which will be shown later.

For convenience of description, we will term the jack J9 the regular answering jack, and the associated jacks J7 and J8 regular 20 multiple jacks. In a like manner J12 will be termed the regular through switching jack, and the associated jacks J10 and J11 may be termed through switching multiple jacks. The functions and uses of jacks J7, 25 J8 and J9, and J10, J11 and J12 are the same respectively. So for the convenience of description, we will refer to jacks J9 and J12 respectively, omitting mention of their said multiplied jacks. It will be noted that 30 there are additional lamps j_{11} and j_{18} associated with jacks J9 and J12 respectively. The said lamps are for the purpose of incoming signals. Their control and functions will be described later.

35 In order to convey a calling signal to the desired station s_6 from A4 with plug p_1 in jack J6, the following physical operations and incidental electrical functions will take place:—The operator at A4 will depress the 40 pushkey n_3 , thus opening the circuit from ground G through conductor $1e$ of plug p_1 by way of jack terminal e_{18} ; contacts $5c$ — $6c$ of said n_3 ; contacts c_3 — c_4 and c_1 — c_2 of pushkeys n_2 and n_1 respectively; to battery 45 B1 by way of terminals a_{14} — a_{15} of relay R2, thus deenergizing said relay. Contacts a_{11} — a_{12} applying negative current from battery F to terminal b_6 are opened and contacts a_{12} — a_{13} are thereafter made, applying 50 positive current from battery B1 to said terminal b_6 . It is because of this lapse in current during the interval of changing polarity that the relay R11, Fig. 3, is given the retarded release characteristic previously mentioned. Contacts a_7 — a_8 , and a_9 — a_{10} are 55 opened, disassociating contacts c_{11} and c_{14} of relay R4 from direct connection to terminals 1 and 2 respectively. The positive current now applied to terminal b_6 of relay R5 follows the same course as the negative current before in reaching G3, but due to the 60 directional characteristics of relays R5, Fig. 4, R7, Fig. 3, and R17, Fig. 5, the following circuit changes will ensue:

65 The armature b_5 of relay R5 will move in

the indicated minus direction closing its contacts b_1 — b_2 and b_3 — b_4 . However, the circuit including the said contacts will still be open at contact a_1 , since R1 is energized.

The armature relay R7 will move in the indicated plus direction, thus opening its contacts g_{12} — g_{13} , and g_{14} — g_{15} , and in turn the helix circuit of dependent relay R9, incidentally opening the contacts g_{33} — g_{34} , and g_{35} — g_{36} , opening the telephonic circuit 75 between terminals 3 and 4, and 5 and 6.

The armature of relay R17, Fig. 5, will move in the indicated minus direction, thus opening its contacts f_{44} — f_{45} , and f_{46} — f_{47} and closing its contacts f_{40} — f_{41} , and f_{42} — f_{43} . As a result of these functions, conductor $6i$ is opened, thus extinguishing the associated lamps j_7 , j_9 , j_{12} , j_{14} , j_{16} , and j_{19} .

However, as will be seen later, this is for only a short interval while a signaling impulse is applied; also, the circuit from battery B3 is closed through relay R14 by way of its terminals f_{19} and f_{18} through the said contacts of relay R17 through relay R16 by way of its terminals f^{35} — f^{34} to ground G3 90 by way of contacts f_3 — f_4 , relay R12. Incident to the actuation of relay R14, its dependent relay R15 is actuated due to closing of circuit from battery B3 by way of its helix terminals f_{32} and f_{33} ; contacts f_{21} — f_{20} of relay R14 to terminal f_{18} of said relay; thus placing relays R14 and R15 in multiple relation. Contacts f_{22} — f_{23} will close the circuit from ground G3 through relay 95 R7 to battery B3 by way of conductor $3i$. 100 The function of relay R7 is to disassociate the relay R19 which is bridged across the terminals e_{25} and e_{26} of answering jack J9; to incidentally close circuit of lamps j_8 , j_{10} , j_{13} , j_{15} , j_{17} , j_{20} to ground G3 by way of its contacts k_3 — k_4 ; causing said lamps to glow during the duration of the signaling impulse; to open conductor $10i$ at contacts k_1 — k_2 of said relay. Contacts f_{24} — f_{25} will

short-circuit terminals e_4' and e_8' of repeating coil C2, and also terminals f_{39} and f_{48} of relay R17 respectively, however not altering the operative function of said relay by so doing. Ringing or signaling current from source P3, which may be of the usual alternating character, is impressed serially upon terminals e_1' and e_5' of repeating coil C2 by way of contacts f_{26} — f_{27} and contacts f_{29} — f_{30} respectively of relay R15. The circuit through primary sections of said repeating coil is by way of conductor between its terminals e_2' and e_1' . The ringing current is thus inductively transformed to pure loop current, which is projected from terminals e_3' and e_7' across the line terminals 110 7 and 8 and out upon the line D across which the signal device at station s_6 is connected in bridge, actuating said signal device. Coincidentally, current from source P3 is applied to

115 terminals e_3' and e_7' across the line terminals 120 7 and 8 and out upon the line D across which the signal device at station s_6 is connected in bridge, actuating said signal device. Coincidentally, current from source P3 is applied to conductors $4i$ and $5i$ through contacts 130

*f*31—*f*30—*f*29, and *f*28—*f*27—*f*26 respectively of relay R15. Said current applied to conductors 4*i* and 5*i* will actuate the polarized relay R22 through its terminals *f*93—*f*91 by way of contacts *k*13—*k*14 and *k*15—*k*16 respectively of relay 8R. Armature *f*84 of relay R22 in turn will successively make and break contacts *f*82—*f*83, *f*85—*f*86, and *f*87—*f*88, *f*98—*f*90 respectively. The contacts *f*82 and *f*89, and *f*85 and *f*87 are in multiple relation respectively. Therefore, in each contact movement of said armature, circuit from battery B3 is completed through relay R24 by way of its terminals *f*103 and *f*102 through resistance *f*104; through its contacts *f*100—*f*101; through the said contacts of relay R22; through relay R23 by way of terminals *f*96 and *f*95; through contacts *k*9—*k*10 of relay 8R to ground G3. Contacts *f*100—*f*99 are designed to make before contacts *f*101—*f*100 break, to avoid breaking the continuity of circuit described between contact spring *f*100 and battery B3. Relay R24 will lock in its operated position by virtue of obtaining constant ground on its terminal *f*102 by way of its contacts *f*100—*f*99 and contacts *k*9—*k*10 of relay 8R. It will unlock only upon the opening of the latter contacts as by the actuating of said relay upon the insertion of a plug as *p*1, Fig. 2, into jack J12, applying ground G to relay terminal 7*c* by way of jack terminal *e*36 of said relay by way of conductor 1*e* of said plug. Relay R23 will actuate upon closing of said contacts of relay R22, opening circuit from battery B3 through contacts *f*97—*f*98 of said relay R23; through resistance *f*104 through contacts *f*100—*f*99 of relay R24; through contacts *k*9—*k*10 to ground G3. The relay R23, Fig. 5, will remain actuated as long as each series of signaling impulses is maintained by reason of pushkey *n*3, Fig. 5, being depressed successively. The said relay R23 remaining actuated is by virtue of it having a retarded release characteristic, though the contacts of relay R22 remain closed only during a portion of the period of each actuating impulse impressed upon said relay R22, as described. After the vibrations of armature *f*84 of relay R22 cease, the armature of relay 23 returns to normal, thus allowing contacts *f*98—*f*97 to be made and the described circuit including the lamp *j*18 reestablished, causing said lamp to glow. Thus it will be observed lamp *j*18 glows at the cessation of each series of impulses impressed upon relay R22, and then remains glowing until extinguished as by the insertion of plug as *p*1 into jack J12, as described. From the successive glows of said lamp *j*18 the operator observing it can determine what code signal is being sent.

The purpose of resistance *f*104 is to re-

strict current through lamp *j*18, when current from battery B3 is drawn from terminal *f*102, relay R24, through said resistance in place of through relay R23 by way of contacts *f*100—*f*99, as described, after the relay R23 returns to normal, for in this latter position of said relay R23, current from battery B3 through lamp *j*18 reaches ground G3 by way of contacts *f*97—*f*98 and resistance *f*104; through terminals *f*102 and *f*103 of relay R24.

Upon the release to normal of pushkey *n*3 the former condition of circuits ensues, the lines E and D being reconnected. The described cycle of circuits and incidental electrical functions will take place upon each depression of key *n*3, thus signaling current will be impressed back and upon and along line D, while line E is telephonically cut off from said line D in conformity with the successive depressions of said key *n*3 to form any ringing code, as the series of signals to which station *s*6 will respond.

It is to be observed, that while station *s*6 was specifically signaled in code, the signal device, lamp *j*18, was displayed in code over the through switching jack *j*12, and not signal device, lamp *j*11, over the regular answering jack J9, thus indicating to the operator at said jack J12 that not only is a code call being made to signal station *s*6, but that it is coming from station A4 on line E and not from some station on line D. Signals coming from stations along the latter line would be displayed by signal device, lamp *j*11, over the regular answering jack J9, which is directly associated with said line normally. This function will be described later.

Lamp signal devices, *j*7', *j*9, *j*12, *j*14, *j*16, and *j*19 associated with jacks J7, J8, J9, J10, J11 and J12 respectively are in multiple relation. They will glow upon obtaining current by way of conductor 6*i* and contacts *f*44—*f*45 and *f*46—*f*47 of relay R17; thence by way of *f*34 and *f*35 through terminals *f*3—*f*4 to ground G3. This will ensue when a plug as *p*1 is inserted in any of the through switching jacks at station A4, thus indicating to operators at station A5 when the lines are interconnected at station A3 under control of station A4. Aside from this indication, the glowing of the said lamps, or more particularly the lamp *j*19, may be used to indicate to the operator at jack J12, station A5, that the station A4 desires her response.

If through carelessness or coincidence, the operator at A5 should insert a plug, as *p*1, into the regular through switching jack J12 during the course of a series of signals sent from pushkey *n*3, the open relay contacts *f*36—*f*37 of relay R16 will preclude the relays R12 and R13 from operating by way of ground G obtained through conductor 7*i*; by

way of jack terminal $e36$ and plug conductor $1e$. Were not this provision made in contacts of relay $R16$ the consequent actuating of relays $R12$, $R13$, due to the said insertion of plug $p1$, would cause relay $R14$ and its dependent relay $R15$ to not obtain ground $G3$ by way of contacts $f42-f43$, and $f40-f41$ respectively, through relay $R16$ by way of its terminals $f35$ and $f34$ to contacts $f3-f4$ of relay $R12$. Since signaling current is applied to line D by relay $R15$, the incapacitating of relay $R15$ as by the functions consequent to the inserting of plug as $p1$ into $J12$ would interrupt any signal impulses under way. Relay $R16$ is given the characteristic of retarded release, so that this relay will have its contacts open during the entire course of transmitting a signal code, the intervals between signals of the code being assumed to be shorter than the release time characteristic of said relay.

If the code signal for station $A5$, in lieu of that of station $s6$, is made at station $A4$, as described, the operator at station $A5$ will respond by inserting a plug as $p1$, Fig. 1, into through switching jack $J12$, disassociating relay $R22$ as previously described, and also causing relays $R12$ and $R13$ to actuate by way of contacts $f36$ and $f37$ of relay $R16$, as previously described, it being borne in mind that relay $R16$ will return to its normal position in a short interval after the termination of last impulse of the signal code sent from pushkey $n3$. In the said state of the relays $R12$ and $R13$, positive battery $B3$ will be applied to terminal $f38$ of relay $R17$ by way of contacts $f13-f14$ of relay $R13$, and contacts $f8-f7$ of relay $R12$. It will be observed that this positive battery will be in series with the battery F coming from station $A4$ by virtue of a plug as $p1$ being inserted in springjack $J6$, pushkey $n3$ being normal. Jack $J6$ and jack $J12$ are now in telephonic connection through switching cord sets as $p1$ at the respective stations. It will be further observed that should operator at station $A4$ withdraw plug as $p1$ from jack $J6$, the lines D and E would remain interconnected by virtue of the current emanating from battery at station $A5$, as described, finding ground $G1$ by way of terminals $a5-a4$, relay $R1$ at station $A4$.

Should the operator at $A5$ desire to signal the station $A4$, the operation would be to depress the switching cord set ringing key $3k$ corresponding to the signal code of said station $A4$. The functions of relay $8R$ incident to the insertion of the plug into jack $J12$ have been described. The application of current from the source $P2$, over conductors $3p$ and $4p$, Fig. 2, will cause the relay $R18$ bridged between jack conductors $e34$ and $e35$, connected respectively by way of conductors $4i$ and $5i$ to series terminals $f56$ and $f50$ of said polarized relay $R18$ in bridged relation. The latter relay being sensitive to directional currents of either or both polarities, the armature $f56$ of said relay will vibrate responsively incidentally opening its contacts $f55-f56$, $f53-f52$, successively, thus opening the circuit between battery $B3$ through terminals $f17$ and $f16$ of relay $R13$ to ground G of plug $p1$ by way of contacts $f37-f36$, conductor $7i$, jack conductor $e36$ and plug conductor $1e$. The deenergizing of said relay $R13$ will cause the contacts $f13-f14$ to be opened, and the contacts $f14-f15$ to be made, thus applying negative battery H to the described circuits in lieu of positive battery $B3$ formerly applied. Incidental to this, relay $R7$ will be actuated in its indicated plus direction, thus opening its said local contacts which in turn, as previously described, will cause relay $R9$ to be deenergized, opening the telephonic circuit between terminals 3 and 4 , and 5 and 6 . Coincidentally with this, the armature $b5$ of relay $R5$, Fig. 4, at station $A4$, as previously described, will move in its indicated minus direction. Bearing in mind that relays $R1$ and $R2$ are in their normal position, relay $R3$, and successively its dependent relay $R4$, will obtain current from battery $B1$ to ground $G1$ by way of terminals $c2$ and $c1$ of relay $R3$ by way of contacts $b3-b4$, and $b2-b1$ of relay $R5$; and contacts $a1-a2$ of relay $R1$. Also, current from battery $B1$ will find ground by way of terminals $c16$ and $c15$ of relay $R4$; through contacts $c4-c3$ to common terminal $c1$ of relay $R3$; from whence it reaches ground $G1$ as previously traced. Signaling current from source $P1$ is now being applied over conductors $1p$ and $2p$ by way of contacts $c12-c13-c14$ and $c9-c10-c11$ respectively serially through primary windings of repeating coil $C1$ by way of section terminals $d1$, $d2$, and $d6$, $d5$; to line terminals 1 and 2 inductively from secondary windings by way of section terminals $d7$, $d8$, and $d4$, $d3$ of said repeating coil $C1$, and contacts $c7-c8$ of relay $R8$; also to apply signaling current across signal device $D2$ by way of contacts $c9-c10-c11$, and $c12-c13-c14$ of relay $R4$; over conductors $i1$ and $i2$; through contacts $11r-10n$ and $9r-8r$ of relay $2R$; actuating said signal device in accordance with code sent by key $k3$ at station $A5$, and thereby apprising the operator at jack $J6$, station $A4$, that her response is desired. Connection is then made by inserting plug as $p1$ into jack $J6$, the functions of which operation has been described. The operator at station $A4$ will know the signal came from station $A5$ by virtue of signal device $D2$ displaying and not signal device $D1$. It will be observed that since signaling current has been applied across line terminals 1 and 2 simultaneously with applying

it across terminals of signal device D2; all signal devices at stations along line D adapted to respond to currents of the character impressed will actuate in conformance with 5 the code displayed by the signal device D2 as described.

Since the relay R3 must act in response to relay R5 before relay R4 can apply ringing current to the line terminals and to the 10 auxiliary signal device D2 over jack J6, and that an appreciable element of time will elapse during the completion of this cycle of operations, currents of a momentary nature will not produce a false signaling 15 effect.

It will also be observed that since the armatures of relays R6 and R8 vibrate or move in response to currents of proper character being applied to them from the line, 20 these armatures may be adapted to evidence such passage of current in an auditory or visual way, and therefore used as a signal device incidentally.

If it is desired to signal the station A4 25 from station A3, for instance, plug as p_1 will be inserted in one of the multiplied jacks J7 and J8. Knowing the functions of said plug p_1 the signal device D3 will be disassociated from line E by virtue of relay 30 4R actuating and opening its contacts g_{51} — g_{52} and g_{53} — g_{54} respectively. Signaling current is then applied to the line E, at the terminals 1 and 2, station A4, by depressing ringing key $3k$ in conformity therewith. 35 At station A4 the signal current will find its way over conductors i_5 and i_4 to the signal device D1 by way of contacts $3r$ — $4r$ and $5r$ — $6r$. Upon the operator at station A4 40 recognizing her code signal as displayed by signal device D1, she will respond by inserting plug as p_1 into jack J3. The function of plug p_1 being known from previous description, the relay 1R will actuate and disassociate signal device D1 and also allow 45 the said operator to have telephonic access with the calling station.

If the operator at station A3, in lieu of inserting plug as p_1 into multiplied jacks J8' and J9', had inserted said plug into 50 multiplied jacks J6' or J7', in lieu of actuating relay 4R, the relay 3R would be actuated thereby, not only disassociating the contacts g_{52} and g_{54} of relay 4R, and incidentally the signal device D3, by opening 55 contacts g_{44} — g_{45} and g_{46} — g_{47} respectively of said relay 3R, but it would also disassociate the polarized relay R6, which was connected in bridge by way of said contacts of relay 3R across terminals 3 and 4. Removing 60 relay R6 thus opens any possible circuit path to manipulating currents between terminals 3 and 4, and 5 and 6 respectively, thus making it impossible to interconnect the lines E and D remotely from either stations A4 or A5.

The signal being displayed by device D1 in place of device D2, as in case before described, indicates to the operator at jack J3 that the call is coming from somewhere along line E and not from the remote line D. 70 There will be no actuations of any of the relays in the associated circuits other than those specifically mentioned, nor will there be any current of a manipulating nature applied along the lines E or D. 75

In a like manner inserting a plug as p_1 into jacks J12' or J13' and transmitting signal by depressing key $3k$, signal device j_{11} associated with jack J9, of Fig. 5, may be displayed to gain the response of the 80 operator at said springjack J9, but in this instance the lamp signal device j_{11} will glow in response to movements of relay R19 and the dependent relays R21 and R20, the functions of which will conform to the 85 functions as described previously with reference to relays R22, R24 and R23 toward their dependent lamp signal device j_{18} .

If the operator at station A3, in lieu of inserting plug as p_1 into multiplied jacks 90 J12' and J13', had inserted said plug into multiplied jacks J10' or J11', actuating relay 6R, the relay 5R would be actuated thereby, not only disassociating the contacts g_{63} and g_{65} of relay 6R and incidentally the signal 95 device D4 by opening the contacts g_{57} — g_{58} and g_{59} — g_{60} respectively of said relay 5R, but it would also disassociate the relay R8, which was connected in bridge by way of said contacts of relay 5R across terminals 100 5 and 6. Removing relay R8 thus opens any possible circuit path to manipulating currents between terminals 3 and 4, and 5 and 6 respectively, thus making it impossible to interconnect the lines E and D from either 105 stations A4 or A5, as before.

It will be observed that by employing the common type of cord connecting pair shown in Fig. 2, interconnection of the lines D and E at station A3 may be made manually by 110 access to one of jacks J6', J7', J8', J9' and one of jacks J10', J11', J12' and J13' respectively. The manual operations in such case disregard the fact that remote control switching equipment is associated. 115

Should operator at station A3 apply bridged signaling current along line leading to terminals 7 and 8 of station A5, relay R19, which is bridged between said terminals by way of contacts on relay 7R will 120 correspondingly vibrate; contacts f_{64} — f_{66} and f_{68} — f_{70} being alternately closed. Terminal f_{72} and spring f_{77} are applied to ground by way of contacts k_1 — k_2 of relay 7R. Thus free pole of calling lamp j_{11} will be 125 grounded through the winding of relay R20 while said contacts are closed. Relay R20 will actuate, as well as relay R21; the latter in multiple with lamp j_{11} . Relay R21 will lock to ground on spring f_{77} . Relay 130

R20 has a slow release characteristic so will remain actuated during brief lapses of energizing current, as when relay R19 returns to normal position between the ringing periods of the code. Lamp j11 will therefore extinguish between the ringing periods of the code. However, upon a prolonged lapse, as at the termination of the signal series, relay R20 will deactivate and connect ground from spring f77, through resistance f76 to lamp j11, causing said lamp to glow until the operator answers by inserting switching plug P1 into spring jack J9 and operating relay 7R and opening contact k1. Thus, after the lamp j11 effects specific glows in response to elements of code signals, it glows permanently. As described in relation to F104, F76 may have a resistance value different than R20, so the permanent glowing can be distinguished by an intensity different than the transient glows.

Referring to Figs. 6 to 11 inclusive:

At top of rack, member 44 is pivoted on bolts 44a and 44b and is adapted to tilt into position shown in 44c, Fig. 8. Said member 44 carries terminal rack 26 which carries twelve insulated terminals i5', i4', i3', i2', i1', 5e', 4e', 3e', 2e', 1e', and 6e', said terminals adapted to engage stationary insulated terminals i5, i4, i3, i2, i1, i'', 5e'', 4e'', 3e'', 2e'', 1e'', 6e''. The latter two sets of terminals connect directly to correspondingly designated terminals of wiring shown in Fig. 4. Thus swinging the rocker arm 44 so its carried terminals are disengaged from their companions stationary terminals will completely disassociate the relays R1, R2, R3, R4, R5, and repeating coil C1 from the line E, Fig. 4, but will not disassociate the jack and signal equipment shown in the lower part of Fig. 4, allowing the line E to be used normally.

42a, Fig. 8, shows the member 42 tilted outward to allow inspection of relays R3 and R4. The member 42 is retained in normal position by gravity catch shown in three positions in Fig. 11; said catch resting against flange of angle iron 48. By depressing outer end of catch 38 to the position 38b the member 42 can be tilted outward on its pivots 46 and 46a. 32, 30 and 34 are inverted keyhole shaped slots adapted to detachably engage over round headed studs, carried on angle iron supports 27 and 28 for the purpose of suspending frame 48. 49 is a dustproof, crosstalk proof plate enclosing the back of the frame 48. Repeating coil C1 is mounted on the back of member 49.

All wiring is run as flexible cables from the terminals of apparatus in Fig. 4 to the designated terminals carried by member 26. Said cable is led out through aperture 51 in member 44.

The apparatus consisting of frame 48 and associated equipment can be regarded as a unit and provides ready means of disassociating or substituting equipment by unskilled persons. The auxiliary equipments shown in Figs. 3 and 5 may be readily mounted as specifically shown in reference to Fig. 4.

In the foregoing specifications mention is made of the operating currents passing over the lines D and E in derivation or in parallel. These currents are superposed upon the telephonic currents during sound transmission. It is not necessary to the proper operation or manipulation of the various relays controlling the circuit relations that this derived or parallel current flow shall take place. A current applied over only one of the limbs of the lines D or E, as by opening midway or at any other point one of the limbs of either or both of said lines, or as opening of conductor at terminal g7 of relay R6, will answer all operative and manipulative conditions.

As described, Fig. 1 shows a toll circuit made up of two lines D and E adapted to be interconnected by apparatus shown in Fig. 4, at station A4. It is possible to employ additional sets as Fig. 4, substituted for station s5, for instance, and in such case there would be three independent line sections adaptable to interconnection by the physical operation set forth.

It is to be understood that the present invention does not contemplate broadly the interconnection of toll lines of the character shown herein, but is directed more particularly to improvements over an application filed by Friendly, Serial No. 34,666, June 17, 1915. There are various new features in the present application and which are being claimed herein, such as the use of signaling devices displayed at the interconnection point to indicate when the lines are interconnected; further, when an operator inserts a plug in the through switching jack for connection to the far line, a signal is displayed at the controlling station of the far line to indicate that the lines are interconnected; further, means at the intermediate interconnecting station for preventing interconnection of the lines from the other stations; further, means for rendering impossible interference with a code signal on the remote line by a remote station, that is, for example, if the operator at A4 plugs into a through switch jack as J6, and rings a station on line D, as S6, the operator at A5 is prevented from interfering with the code ring, should she carelessly plug into a through jack J10, because of the operation of relay R16; further, that signals at interconnecting station are (and jacks can be) disassociated during through signaling and during through conversation; further, that

- a signal will automatically display at a station, as station A5, when lines are caused to be interconnected from a remote station, as from station A4, for instance; further, that 5 the far line or through switching jacks are normally disconnected from the line and are connected only when the operator plugs into a through switching jack, as J12, provided relay R16 is at normal.
- 10 The mention of these various points of novelty is merely by way of illustration, and it is by no means exhaustive.
- The term "multiple" in the specifications and the subjoined claims is not intended to 15 limit or prescribe the invention to uses where any element of equipment, as a springjack or lamp appears in duplicate; it refers to a greater multiplicity, or as used singly.
- 20 Having thus described our invention, what we claim as new, and desire to secure by United States Letters Patent is:
1. In apparatus for effecting interconnection between lines wherein currents of 25 opposite direction are employed to effect interconnection; a near line and station, a far or remote line and station, lamp signals at the stations, means for causing a signal to be displayed at a station on the 30 remote line, a polarized relay bridged between the conductors of the telephone line, said means being under control of said relay, a switching cord circuit under control of the operator at the station controlling 35 the connection, a key in the said cord circuit, and actuating currents for the relay applied by said key through a plug of said switching cord circuit inserted in the jack connected at said controlling station 40 of the line, substantially as described.
  2. In a telephone system, a first and a second line, a first station on the first line, a second station common to the said lines, a polarized relay at the second station, means 45 at the first station for controlling said polarized relay, a second relay controlled by said polarized relay to interconnect said lines, and a third relay bridged between the limbs of said first line, and operative to 50 prevent the actuation of said second relay.
  3. In a telephone system, a first and a second line, a first station on the first line, a second station common to said lines, a polarized relay at the second station, means 55 at the first station for controlling said polarized relay, a second relay controlled by the polarized relay for interconnecting said lines, a third relay connected to the first line, a fourth relay connected to the other line, and normally closed contacts on said 60 third and fourth relays included in the control circuit of said second relay.
  4. In a telephone system, a first and a second line, a first station on the first line, a second station common to said lines, a po-

larized relay at the second station, means at the first station for controlling said polarized relay, a second relay under control of said polarized relay for interconnecting said lines, and a third relay operative over 70 the first line having normally closed contacts in the control circuit of the second relay.

5. A telephone system comprising telephone lines, an interconnection point common to a first and a second line, an operator's station on each line, a first relay responsive to directional currents to cause the lines to be connected; sources of current, means at one of said stations for applying 80 current of the proper polarity to so operate said relay, a second neutral relay in a derived circuit of said first relay adapted to actuate upon current of either polarity traversing it, and a signal device responsive to 85 the actuation of said last relay.

6. At an interconnection point common to two lines adapted to be connected, a relay in a derived circuit between said lines, means whereby said relay will become actuated from current applied from over said derived circuit; a signal device associated with said relay, the actuation of said relay causing the lines to become connected and cause said signal device to actuate indicating such state.

7. A telephone system comprising two telephone lines, a first station on one of the two lines, a second station common to both said lines, a third station on the second of said lines, a relay at said second station adapted to interconnect said lines operative from current projected from said first station, means for projecting such current, and a signal device at said third station which will display during the time current causing lines to be interconnected is acting.

8. A near and a remote line, a first station on said near line, a second station common to both said lines, a third station on said remote line, a first relay at said second station in a derived circuit between said lines, means for applying current of prearranged character through said first relay to interconnect said lines, a switching plug and spring jack, a pole-changing relay bridged between the conductors of said near line responsive to currents applied from the switching plug used to gain access to said 120 near line through the spring jack, a first signal device and second signal device at the remote station, a third relay on said remote line sensitive to changes of current polarity adapted to cause the first signal device to 125 display upon insertion of said plug into said springjack and to extinguish when currents are applied from said switching plug to operate said pole-changing relay and to thereupon cause the second signal device to 130

display, and means for applying such currents.

9. A telephone system comprising a first telephone line and a second telephone line, 5 an interconnection point common to and interlinked with said first and said second line, a source of current, a relay responsive to directional currents from said source under control at a station on the first line, said 10 relay adapted to cause a telephonic connection between the said lines; and means under control of an operator at said interconnection point to disassociate said relay from either or both lines at will.

15 10. In a telephone system a springjack and a switching plug adapted to register with the contact springs thereof; a line leading from two contact springs of said springjack; a source of ringing current 20 adapted to be applied to said line through said switching plug; a relay responsive to said current in a bridge between the limbs of said line; a source of direct current, and a pole-changing relay responsive to said 25 first relay and adapted to alternatively apply different current polarities to a conductor connected in a derived circuit of said line.

11. A telephone system comprising a telephone line, an operator's station on said line, 30 a sending station on said line, a lamp signal at the operator's station, a receiving device at the operator's station responsive to code signaling ringing currents from the sending station for causing said lamp to 35 glow according to the code signal and thereafter extinguish, and automatic means for causing said lamp to light and glow continuously after a predetermined period following the cessation of the code signaling.

12. A telephone system comprising a telephone line, an operator's station on said line, a sending station on said line, a lamp signal at the operator's station, a polarized relay at the operator's station responsive to code signaling currents from the sending station for causing said lamp to operate according to the code signal, and a slow acting relay operative after a predetermined period 45 following the cessation of the code signaling for causing said lamp to glow continuously.

13. A telephone system comprising a telephone line, an operator's station on said line, 55 a sending station on said line, a signal device at the operator's station, a relay at the operator's station responsive to code signaling ringing current from the sending station for causing said lamp to glow according to the code signal and thereafter extinguish, and means for automatically 60 causing said lamp to light and glow continuously upon cessation of the code signaling.

65 14. A telephone system comprising a tele-

phone line, a sending station on said line, an operator's station on said line, a polarized relay connected to said line at the operator's station, a signal device at the operator's station, means for applying signaling current in code at the sending station for operating said relay and lamp according to the code signal, and means responsive to the cessation of the code signaling for automatically causing said lamp to glow continuously.

15. A telephone system comprising a telephone line, an operator's station on said line, a lamp signal at the operator's station, a relay at the operator's station responsive to code signaling currents from the sending station for causing said lamp to operate according to the code signal, and automatic means for shifting circuit connections through said lamp responsive to the cessation of the code signaling for causing said lamp to glow continuously.

16. A telephone system comprising a telephone line, two signal devices at a station on said line, two sending stations on said line, a lamp signal at each signal device, a relay at each signal device, each relay being responsive to code signaling ringing currents from one of the two sending stations for causing the corresponding lamp to operate according to the code signal, and automatic means for causing said lamp to glow continuously responsive to the cessation of the code signaling.

17. A telephone system comprising a telephone line, an operator's station on said line, a plurality of telephones on said line, a lamp signal at the operator's station, a relay at the operator's station responsive to code signaling ringing currents from any of the telephones for lighting said lamp according to the code signal and thereafter extinguishing said lamp, and automatic means for causing said lamp to light and glow continuously after a predetermined period following the cessation of the code signaling.

18. A telephone system comprising a telephone line, an operator's station on said line, other stations on said line, means for signaling between said other stations, means for signaling said other stations from the operator's station, and means for preventing signaling said other stations from the operator's station when signaling is being effected between said other stations.

19. A telephone system comprising a telephone line, an operator's station on said line, other stations on said line, a first means at said operator's station controlled from one of said other stations for signaling a second one of said other stations on said line, other means at said operator's station of signaling certain of said other stations, and means for rendering the said other signaling means ineffective during the operation of said first

signaling means whereby the operator can not interfere during the signaling.

20. A telephone system comprising telephone lines one and two connected at an intermediate interconnecting point, an operator's station on each line, a telephone on line one between the operators' stations, means at the operator's station on line one controlled from the other operator's station 10 for signaling the telephone on line one, and means to prevent the operator at the station on line one from interfering when such signaling is being effected from her station to the telephone.

21. A telephone system comprising telephone lines one and two terminating at an intermediate interconnecting point, an operator's station on each line, a telephone on line one between the operators' stations, 20 means at the operator's station on line one controlled from the other operator's station for signaling the telephone on line one, and means to prevent the operator at the station on line one from interfering with signaling 25 when signaling is being effected from her station to the telephone.

22. A telephone system comprising a telephone line, an operator's station on said line, other stations on said line, a normally disconnected jack at the operator's station for 30 said line, an operator's plug ended cord circuit, a relay responsive to the insertion of the cord plug into said jack to connect said jack and line, means at said operator's station controlled from one of said other stations for signaling a second one of said other stations on said line, and means for rendering 35 said relay ineffective during the operation of said signaling means whereby an operator cannot interfere during the signaling.

23. In a telephone system a telephone line extending from a first operator's connecting station to a second station, a second telephone line extending from the second station 45 to a third operator's connecting station, a near line jack and normally disconnected switching jack for the first line at the first operator's station, a plug ended cord circuit at said first station, and means whereby 50 when the cord plug is connected to the switching jack said jack is connected to the first line and the first line connected through the second station to the second line, and when said cord plug is connected to the line 55 jack connection is established with the first line only.

24. In a telephone system a telephone line extending from a first operator's connecting station to a second station, a second telephone line extending from the second station 60 to a third operator's connecting station but said lines being normally disconnected at said second interconnecting station, a near line jack and a normally disconnected 65 switching jack individual to the first line

at the first operator's station, a plug ended cord circuit at the first station, and relay mechanism at the first station and at the interconnecting station whereby when said plug is connected to the switching jack said 70 jack is connected with the first line and the first line connected with the second line, and when the plug is connected to the line jack connection is established with the first line only. 75

25. In a telephone system a telephone line extending from a first operator's connecting station to a second station, a second telephone line extending from the second station to a third operator's connecting station 80 but said lines being normally disconnected at said second interconnecting station, a near line jack and a normally disconnected switching jack individual to the first line at the first operator's station, a plug ended cord 85 circuit at the first station, and relay mechanism at the first station and at the interconnecting station whereby when said plug is connected to the switching jack said jack is connected with the second line, and when the plug is connected to the line jack connection 90 is established with the first line only, and means controlled from another station to prevent the connection of the switching jack with the line. 95

26. In a telephone system, a telephone line extending from a first operator's connecting station to an intermediate station, a second telephone line extending from the intermediate station to a third operator's connecting station, a near line jack and a switching jack individual to the first line at the first operator's station, a plug ended cord circuit at the first station, means whereby when said plug is connected to the line jack 100 connection is established with the first line only, a relay operated when the plug is connected to the switching jack to connect said jack and line, relay mechanism at the interconnecting station also responsive to the insertion of the plug in the switching jack whereby connection is extended over the first line to the second line, subscribers' telephones connected to the second or far line, means whereby the operator at the first station may 110 signal the telephones on the far line, and means controlled from the operator's connecting station on the far line to prevent the connection of the switching jack and line 115 through the connecting relay. 120

27. A telephone system comprising a near line and a far line, an intermediate connecting station at which said lines terminate, an operator's switching station at another point on the near line, other stations on the near 125 and far lines, a near line switching equipment and a far line switching equipment individual to the near line at its operator's connecting station, one of said equipments being normally disconnected, an operator's 130

5 plug ended cord circuit for connection to the near line switching equipment for direct connection with the near line only, means included in the far line switching equipment responsive to the connection of the operator's cord circuit with the far line switching equipment for connecting this last said equipment with the near line, and means responsive to the last said connection for connecting the two lines.

10 28. A telephone system comprising two telephone lines terminating at an intermediate interconnecting station, through and near line switching equipment associated with an operator's station on each line, means for connecting said lines together or using either line independently at the intermediate station, and means for operatively disconnecting the through switching equipment of either line responsive to a call over the corresponding line from the intermediate station.

15 29. A telephone system comprising two telephone lines terminating at a central interconnecting station and permanently paired therewith, an operator's connecting station on each line, means whereby an operator at one station may signal the substation on the far line, relay mechanism at the central interconnecting station controlled by the calling operator for interconnecting said lines, and a signal device at the interconnecting station operated for indicating when said lines are interconnected, and means at the intermediate station for preventing interconnection of the lines from the operators' stations.

20 30. A telephone system comprising a telephone line extending from one operator's connecting station to an intermediate exchange, a second line from the intermediate exchange to a third operator's connecting station, means whereby either operator may extend a connection to the near line or over the near line to the far line, and a lamp signal at the far line operated responsive to a through connection to indicate that such through connection is being effected.

25 31. A telephone system comprising a telephone line extending from one operator's connecting station to an intermediate exchange, a second line from the intermediate exchange to a third operator's connecting station, means whereby either operator may extend a connection to the near line or over the near line to the far line, and lamp signals at the intermediate and far line connecting stations responsive to a through connection to indicate that such through connection is being effected.

30 32. A telephone system comprising two telephone lines terminating at a central interconnecting station, an operator's connecting station on each line, said operators' stations being at different exchanges, near line

switching equipment and far line switching line one between the operators' stations, a calling lamp signal for each switching equipment, an operator's cord circuit, and means responsive to the connection of said cord circuit with the far line switching equipment to disconnect both calling signal lamps.

33. A telephone system comprising two telephone lines terminating at a central interconnecting station and permanently paired therewith, an operator's connecting station on one line, a station on the second line, means whereby the operator at the operator's station may signal the station on the other line, relay mechanism at the central interconnecting station controlled by the calling operator for interconnecting said lines, a signal at the interconnecting station, and means for disconnecting the signal at the central interconnecting station during a through connection from the operator's station on the first line to the station on the other line.

38 34. In a telephone system a springjack, a switching plug adapted to register with the contact springs of the springjack, a line leading from the telephonic springs of the said springjack, a source of ringing current, means for supplying said source of ringing current through said plug in bridge of the limbs of the line, a relay responsive to said ringing current connected in bridge of the limbs of the line, a source of direct current controlled by said relay, and means for applying the said direct current over a path including a derived circuit of the line.

43 35. In a telephone system a springjack, a switching plug adapted to register with the contact springs of the springjack, a line leading from the telephonic springs of the said springjack, a source of ringing current, means for applying said source of ringing current through said plug in bridge of the limbs of the line, a relay responsive to said ringing current connected in bridge of the limbs of the line, a source of direct current controlled by said relay, and means for applying the said direct current over a path including a simplex circuit of the line.

48 36. In a telephone system a first line arranged to be connected to a second line through connecting mechanism controlled remotely, an operator's switching cord and plug, a first source of ringing current, means for connecting said plug with the first line and for operating said switching mechanism for interconnecting the lines, a relay responsive to the ringing current connected in bridge of the limbs of the first line, a second relay for applying a second source of ringing current to the second line controlled by said first relay, means for applying ringing current through the plug and across the limbs of the line in bridge, and means where-

- by when ringing current is applied to the first line the second relay will apply ringing current to the second line for the period of said application of ringing current to the 5 first line.
37. In a telephone system a first line arranged to be connected to a second line through connecting mechanism controlled remotely, an operator's switching cord and plug, a source of alternating current, means for connecting said plug with the first line and for operating said switching mechanism for interconnecting the lines, a relay responsive to alternating current connected in 10 bridge of the limbs of the first line, a second relay for applying ringing current to the second line controlled by said first relay over an operating conductor, means for applying the source of ringing current through 15 the plug and in bridge of the limbs of the first line, and means whereby when the ringing current is applied to the first line the second relay will apply ringing current to the second line for the period of said application of ringing current to the first line.
38. In a telephone system a springjack, a switching plug adapted to register with the contact springs of the springjack, a line leading from the said springjack, a source of 20 ringing current, means for applying said source of ringing current through the plug in bridge of the limbs of the line, a relay responsive to said ringing current connected in bridge of the limbs of the line, two sources 25 of direct current controlled by said relay, a second relay differently responsive to the said two current sources, and means whereby when the first said relay operates the said second relay will be caused to correspondingly operate.
39. In a telephone system a springjack, a switching plug adapted to register with the contact springs of the springjack, a line leading from the said springjack, a source 30 of alternating current, means for applying said source of alternating current through the plug in bridge of the limbs of the line, a relay responsive to said alternating current connected in bridge of the limbs of the line, two sources 35 of direct current controlled by said relay, a second relay differently responsive to the said two current sources, and means whereby when the first said relay operates the said second relay will be caused to correspondingly operate.
40. In a telephone system a trunk line and coöperating second line, an electromagnetic device on the second line, a first relay responsive to ringing current connected in 40 bridge of the telephonic limbs of the trunk, a source of ringing current and means for applying it in bridge of the telephonic limbs of the trunk to operate the said first relay, a second source of ringing current and a 45 means including a second relay for applying the said current to the second line, a control circuit intermediate of the first relay and the second relay including talking conductors of the trunk line whereby when the first source of ringing current is applied to operate the 50 first relay the said second relay will be caused to apply ringing current along the second line to operate the said signal device.
41. In a telephone system a trunk line and a coöperating second line, a first relay responsive to ringing current in bridge of the telephonic limbs of the trunk, a source of ringing current and means for applying it in bridge of the telephonic limbs of the trunk to operate the said first relay, a second source of ringing current and means including a second relay for applying it to the second line, a control circuit intermediate of the first relay and the second relay including talking conductors of the trunk line whereby when the first source of ringing current is applied to operate the first relay the said second relay will be caused to apply ringing current along the second line, and a means to disassociate the trunk line from the second line telephonically for the duration of the application of the said first source of ringing current to operate the first said relay.
42. In a telephone system a trunk line and a means controlled over an operating circuit 95 from a station connected to the trunk for causing the trunk to be connected with a second line, a source of ringing current and means for applying it in bridge of the limbs of the trunk, a relay responsive to the ringing current connected in bridge of the limbs of the trunk, a second source of ringing current and a second relay connected to a talking conductor of the second line for effecting the application of said second source to said 100 second line whereby when the first said ringing current is applied to operate the first said relay the second said relay will cause the said second source of ringing current to be applied along the said second line for the 105 duration of the application of the signaling current in bridge of the limbs of the trunk line.
43. In a telephone system a calling switching plug and cord, a called line, a trunk line, a springjack for connecting the switching plug to the trunk line, means controlled from the calling end of the trunk for connecting the trunk to the called line, operator controlled means for applying ringing current to the trunk from the calling end, a second source of ringing current for application to the called line, and repeating relays progressively controlled over successive portions of the talking conductors responsive to the operator controlled means whereby when ringing current is applied to the trunk line the second source of ringing current is applied to the called line.
44. In a telephone system a calling line, a 110

- called line, an operator controlled link connecting said lines, means controlled by the operator for applying ringing current to the calling line end of the link, a second source 5 of ringing current for application to the called line, and repeating relays progressively controlled over successive portions of the talking conductors responsive to the operator controlled ringing current for applying 10 the second source of ringing current to the called line.
45. In a telephone system, a first, a second and a third line, means for connecting the first and second and the second and third 15 lines together, a signal device on the third line, a source of ringing current and means for applying it in bridge of the talking limbs of the first line, a relay in bridge of the talking limbs of the first line responsive to 20 the said ringing current, a second relay connected to the talking limbs of the second line which will operate responsive to current controlled by the operation of the first relay, an additional source of ringing current and 25 means controlled by the second relay for applying it to the third line whereupon applying the signaling current to the first line will cause an independent source of ringing current to be applied to the third line to operate 30 the signal device thereon.
46. In a telephone system a first, a second and a third line, means for connecting them for telephonic service from the first to and including the third line, a calling station on 35 the first line, an electromagnet device on the third line, a source of ringing current and means for applying it in bridge of the talk-
- ing limbs of the first line, a relay in bridge of the talking limbs of the first line responsive to the said ringing current, a second relay connected to the talking limbs of the second line operative responsive to current controlled by the operation of the first relay, an additional source of ringing current and 40 means controlled by the second relay for applying the latter source of ringing current to the third line, whereupon applying the signaling current to the first line will cause said additional source of ringing current to be applied to the third line to operate 45 the electromagnetic device thereon.
47. In a telephone system a first, a second and a third line, means for connecting them for telephonic service from the first to and including the third line, signal devices on the 50 second and the third lines, a source of ringing current and means for applying it in bridge of the talking limbs of the first line, a first relay in bridge of the talking limbs of the first line responsive to the said ringing current, means responsive to the first relay when actuated by the application of ringing 55 current to the first line to apply ringing current to the third line to operate the signal device thereon and operatively disassociate 60 the signal from the second line.

Signed by us at Portland, county of Multnomah, and State of Oregon, in the presence of two witnesses, this 22nd day of May, 1915.

HERBERT M. FRIENDLY.
ARCHIBALD E. BURNS.
